UNITED STATES PATENT OFFICE.

CHARLIE FERNANDY SPENCER, OF ALEXANDRIA BAY, NEW YORK.

COUPLING FOR SECTIONAL CONVEYER-SPOUTS.

SPECIFICATION forming part of Letters Patent No. 757,573, dated April 19, 1904.

Application filed October 17, 1903. Serial No. 177,464. (No model.)

To all whom it may concern:

Be it known that I, CHARLIE FERNANDY SPENCER, a citizen of the United States, residing at Alexandria Bay, in the county of Jefferson and State of New York, have invented new and useful Improvements in Couplings for Sectional Conveyer-Spouts, of which the following is a specification.

This invention relates to improvements in couplings for the sections of conveyer-spouts such as are used in handling grain, coal, or other material to carry the same from one elevation to another, the object of the invention being to provide coupling means for the hollow conical sections of a flexible conveyer, the couplings being of such construction that one section of the conveyer may be held in sliding connection with the adjacent one and permitted to assume such angle with respect thereto as may be desired to give the proper curve to the conveyer.

The invention consists in the construction and combination of the parts, as will be hereinafter set forth, and pointed out in the claim.

In the accompanying drawings, Figure 1 is a side elevation of a part of a conveyer-spout connected by couplings made in accord with my invention. Fig. 2 is a side elevation of a modification, and Fig. 3 is also a side elevation of such modification from another point of view.

Referring to the drawings, A designates the sections of the chute or spout, the same being in the form of hollow truncated cones, the smaller end of one section in practice being positioned within the larger end of the adjacent section.

To the exterior of each section A there are secured fixtures B, which maintain in sliding engagement therewith links or rods C. The fixtures B are located adjacent to the larger end of the sections of the chute or spout, being riveted thereto and shaped to retain in sliding engagement therewith one end of a link or rod C, the other end of the link or rod being held in movable and detachable engagement with the fixture on the adjacent section of the spout. Each section of the chute or spout is connected to the adjacent

one by two or more couplings, the links thereof being in sliding engagement with the fixture on one section and in pivotal engagement with the fixture on the adjacent section.

In practice I prefer to provide each section A with couplings made of heavy wire, the part B comprising a bar b bent near its ends so as to be positioned above and parallel with the face of the section to which it is secured. The wire is shaped to provide eyes or loops b' and b'', through which are passed rivets for attaching the fixture to the section A, and there is present an eye b³, with which engages the looped end of the link C. The link C has one end bent at substantially right angles to its main portion, and beyond the bend is an eye c, which encircles the bar b, and upon the other end is formed a loop c' for engagement with the eye b³ of the adjacent fixture. The loop c' permits the coupling to be separated when desired.

In the modified form of my invention the fixtures B' are made of sheet metal or castings and have a recess or slideway for a link C', with an enlarged head positioned at right angles to the body portion of the link. The other end of the link is pivotally and removably attached to a plate having upwardly-projecting lugs to receive a pintle, said pintle being removable to separate the coupling.

Having thus set forth my invention, what I claim as new, and desire to secure by Letters Patent, is—

A coupling for sectional conveyer-spouts, comprising a fixture rigidly attached to one section of the conveyer, a link one end of which is maintained in sliding engagement with the fixture the other end of the link being in movable and separable engagement with a fixture on an adjacent section of the spout, substantially as shown and for the purpose set forth.

In testimony whereof I have signed my name to this specification in the presence of two subscribing witnesses.

CHARLIE FERNANDY SPENCER.
